(57) **CLAIM**

The ornamental design for a sealed fluid container, as shown and described.

DESCRIPTION

FIG. 1 is a front, bottom-left perspective view of a sealed fluid container according to the new design;

FIG. 2 is a rear, bottom-right perspective view thereof;

FIG. 3 is a top view thereof;

FIG. 4 is a bottom view thereof;

FIG. 5 is a left view thereof;

FIG. 6 is a right view thereof;

FIG. 7 is a rear view thereof; and,

FIG. 8 is a front view thereof.

The broken lines shown represent unclaimed subject matter and form no part of the claimed design.

1 Claim, 5 Drawing Sheets
